US00D751735S

(12) **United States Design Patent**
Swessel et al.

(10) **Patent No.:** US D751,735 S
(45) **Date of Patent:** ** Mar. 15, 2016

(54) **LIGHT FIXTURE**

(71) Applicants: **Mark R. Swessel**, Milwaukee, WI (US); **Norbert Hahn**, Franklin, WI (US); **Tim Muhl**, Slinger, WI (US); **Mark G. Petri**, Mequon, WI (US); **Paul Maly**, Mequon, WI (US); **Charles S. Waugaman**, Mequon, WI (US); **Paul D. Rowlett**, Grafton, WI (US); **Jason Dondlinger**, Bellevue, IA (US); **Matthew C. McNeill**, Mequon, WI (US)

(72) Inventors: **Mark R. Swessel**, Milwaukee, WI (US); **Norbert Hahn**, Franklin, WI (US); **Tim Muhl**, Slinger, WI (US); **Mark G. Petri**, Mequon, WI (US); **Paul Maly**, Mequon, WI (US); **Charles S. Waugaman**, Mequon, WI (US); **Paul D. Rowlett**, Grafton, WI (US); **Jason Dondlinger**, Bellevue, IA (US); **Matthew C. McNeill**, Mequon, WI (US)

(73) Assignee: **RITE-HITE HOLDING CORPORATION**, Milwaukee, WI (US)

(**) Term: **14 Years**

(21) Appl. No.: **29/493,119**

(22) Filed: **Jun. 5, 2014**

(57) **CLAIM**

The ornamental design for "light fixture," as shown and described in FIGS. 1-6.

DESCRIPTION

FIG. 1 is a front view of a first example light fixture. FIG. 2 is another front view of the light fixture of FIG. 1. FIG. 3 is a front view of the light fixture of FIG. 1 showing one of the light emitting rods decoupled from the housing. FIG. 4 is a right side view of the example light fixture of FIGS. 1 and 2. FIG. 5 is a back view of one of the light emitting rods of the example light fixture of FIG. 1; and, FIG. 6 is a front view of one of the light emitting rods of the example light fixture of FIG. 1. The features shown in broken lines form no part of the claimed design.

1 Claim, 6 Drawing Sheets
